[57] CLAIM

The ornamental design for an occupant-propelled vehicle, as shown and described.

DESCRIPTION

FIG. 1 is a front and side perspective view of an occupant-propelled vehicle showing our new design; FIG. 2 is a left side elevational view thereof, the right side being substantially a mirror image of that shown; FIG. 3 is a rear and side perspective view thereof with the rear rack and is a second embodiment of an occupant-propelled vehicle showing our new design; and, FIG. 4 is a bottom plan view of FIG. 3.

Fig. 3.

Fig. 4.
